APPARATUS FOR PRESSING GARMENTS

Sidney J. Bedell, Brooklyn, and Edward Glasser,
Woodside, Long Island, N. Y.

Application October 12, 1938, Serial No. 234,514

9 Claims. (Cl. 38—32)

This invention comprises an improved support for pressing irons which facilitates the lifting and movement of the iron during the pressing operation. More particularly, the invention provides improved pressing apparatus for exerting an upward pull on the pressing iron to relieve the effort required to lift and move the same while permitting free movement of the iron over the pressing board.

Various features of the invention include: A hollow vertical supporting tube which is rotatable on a ball bearing support; an elevated supporting track of relatively short length which is mounted on the hollow tube and movable therewith; a resilient spring for exerting a pull on the iron linked to the supporting tube and located on the opposite side of the tube with respect to the iron; and an iron rest extending from the hollow vertical tube. All of these features, as well as others which will appear hereinafter, cooperate to provide a simplified and highly efficient pressing apparatus which relieves the operator from much of the labor incident to the pressing of garments.

The following is a detailed description of the invention, accompanied by drawings wherein:

Fig. 1 is a perspective view illustrating pressing apparatus constructed in accordance with the principles of the invention;

Fig. 2 is a detail view of the elevated track and roller assembly;

Fig. 3 is a cross-sectional detail view of the ball bearing support for the rotatable hollow tube supporting the iron;

Fig. 4 is a top or plan view of the apparatus of Fig. 1 as applied to a table and long ironing board, particularly suitable for home use;

Fig. 5 is a side view of the apparatus of Fig. 4; and

Fig. 6 is a fragmentary detail view of the ironing board and its pivoted support at one end thereof, along the lines 6—6 of Fig. 5.

Throughout the drawings, the same elements are designated by the same reference numerals.

Referring to Fig. 1, there is shown a hollow vertical tube 1 which telescopes over and is rotatable about a hollow standard 2, mounted on table 11, for supporting a horizontal track 3, a pivotal cross-bar 4 movable longitudinally over the track, a contractile spring 5 at one end of the cross-bar and linked to and rotatable with the hollow tube 1 by means of an extended rod 6, a pressing iron 7 supported at the other end of cross-bar 4 by means of a chain 8, and an iron rest 9 mounted on an arm 10 which is supported from the tube 1. Spring 5 and chain 8 are located on opposite sides of tube 1 and substantially in the same vertical plane with the tube 1. The standard 2 is made hollow for accommodating a gas pipe, or electric wire 12 which

passes up from below the table 11 and hooks onto cross-bar 4 at 13, 13, before finally terminating at the iron for supplying heating energy thereto.

5 The iron rest comprises a horizontal metallic element 14 sufficiently wide to accommodate the iron 7 and provided at both sides with raised flanges, as shown, to prevent the iron from sliding off the rest. Element 14 is supported from the resilient springs 15, 15 which are free to contract and expand over floating pins 16, 16, in turn attached at one end to the horizontal metallic element. The dotted lines indicate the position of the cross-bar 4, chain 8 and iron 7 when used to press a garment resting on the table 11.

The track 3 and associated roller mechanism is indicated in more detail in Fig. 2. The track consists of two parallel bars 3', 3' which are horizontal for the major portion of their lengths 20 and extend downwards at one end and upwards at the other end, as shown, in order to enable the cross-bar 4 mounted between them to move over the tracks freely and to pivot up and down. Over the horizontal portion of each track 3' is a horizontal guide rod 17, and between each bar 3' and associate guide rod there is a roller 18, the two rollers in turn being linked to each other by means of an axle 19 to which the cross-bar 4 is fixedly fastened. The entire track and roller assembly is mounted on a forked or U-shaped element 20 which is fixedly secured by means of a cap 1' to vertical tube 1 and is rotatable therewith. Hence, as the cross-bar 4 is urged to move in response to pressure on the iron, the bar will move with the rollers along the length of the track, and the track as a unit will rotate with movement of the tube 1.

The manner in which tube 1 is mounted is shown more clearly in Fig. 3. Tube 1 is threaded 40 at its top to which is screwed a slightly wider cap 1' whose interior is designed to rest on a ball bearing 21, in turn resting on the closed end of the hollow standard 2. Cap 1' and standard 2 are slightly recessed at those parts which contact ball bearing 21. Access to the ball bearing is obtained merely by lifting hollow tube 1 off the standard 2. To facilitate this, the track 3 can, if desired, first be unfastened from cap 1' by unscrewing U-shaped element 20 from the cap.

50 The improved pressing apparatus of the invention is applicable to both factory and home use. Figs. 4 and 5 show, by way of example only, how the invention can be applied to a home using a relatively long pressing board 21. The pressing board 21 can be supported at one end from a table 11 or other suitable support by means of wooden beams 22 which extend from under the table top and are adapted to slide into hollow iron brackets 23 fastened underneath and to the board. The other end of the pressing board 21

can be supported by means of a pivotally movable support 24 which is attached to the pressing board at 25 by a pin arrangement 26. The other end of support 24 removed from pin 26 is adapted to rest on a wooden block 27. Thus, the pressing board 21 can be removed from the table merely by lifting the support 24 from the block 27 and pulling the board outwards so as to free the brackets 23 from the wooden beams 21. The use of a pivoted support 24 at the narrow end of the board 21 enables the pressing board to accommodate certain garments, such as dresses, which require some space between the pressing board and the table.

The arrangement of Fig. 5, furthermore, differs from that of Fig. 1 in the showing of the hollow tube 1 and standard 2 below the table top, thus enabling the table to be used for other purposes than ironing, merely by lifting the tube 1 and associated elements from the standard 2. To achieve this result, the standard 2 is mounted below the table top, and the cap 1' is lengthened so as to pass through a hole 28 in the table and to extend above the table. The usual track 2, cross-bar 4, spring 5, chain 8, iron 7, etc. are mounted on cap 1' above the table top in the same manner as in Fig. 1, and are not shown to avoid a needless duplication of elements.

What is claimed is:

1. A pressing mechanism comprising a vertical rotatable rod, a bar pivotally supported intermediate the ends thereof and mounted on said vertical rod, a pressing iron supported from one end of said bar, a contractile spring depending from the other end of said bar and fastened to said vertical rod for exerting an upward pull on said iron, whereby said rod, bar and spring are rotatable as a unit in response to movement of said iron to either side of said rod.

2. A pressing mechanism comprising a vertical rod which telescopes over and is rotatable with respect to a fixed supporting standard, a ball bearing between said rod and the top of said standard for facilitating movement of said rod relative to said standard, a bar for supporting an iron at one end thereof pivotally supported intermediate the ends thereof and mounted on said vertical rod, a contractile spring depending from the other end of said bar and fastened to said vertical rod at a point near the lower end of said rod for exerting an upward pull on said iron, whereby said rod, bar and spring are rotatable as a unit in response to movement of said iron to either side of said rod.

3. A pressing mechanism comprising a vertical rotatable rod supporting at its top a horizontal track, a cross-bar pivotally supported intermediate its ends on a roller arrangement movable over said track, a pressing iron supported at one end of said cross-bar, a contractile spring depending from the other end of said bar and fastened to said rod for exerting an upward pull on said iron, whereby said rod, track, bar and spring are rotatable as a unit in response to movement of said iron to either side of said rod.

4. A pressing mechanism in accordance with claim 3, including a support for said rod, and a ball bearing arrangement between said rod and last support.

5. The combination with a pressing mechanism comprising a vertical rotatable rod, a bar pivotally supported intermediate the ends thereof and mounted on said vertical rod, a pressing iron sup-

ported from one end of said bar, a contractile spring depending from the other end of said bar and fastened to said vertical rod for exerting an upward pull on said iron, whereby said rod, bar and spring are rotatable as a unit in response to movement of said iron to either side of said rod, of a table, and a pressing board detachably fastened to said table, the top of said table having an aperture through which said vertical rod extends said rod being mounted below said table top.

6. A pressing mechanism comprising a vertical rod which telescopes over and is rotatable with respect to a fixed supporting standard, a ball bearing between said rod and standard for facilitating movement of said rod relative to said standard, a bar for supporting an iron at one end thereof pivotally supported intermediate the ends thereof and mounted on said vertical rod, a contractile spring depending from the other end of said bar and fastened to said vertical rod for exerting an upward pull on said iron, whereby said rod, bar and spring are rotatable as a unit in response to movement of said iron to either side of said rod, and a cable for supplying heating energy to said iron, said standard being hollow for accommodating said cable for at least a short portion of its length.

7. A pressing mechanism comprising a vertical rotatable rod, a bar pivotally supported intermediate the ends thereof and mounted on the top of said vertical rod, a pressing iron supported from one end of said bar, a contractile spring depending from the other end of said bar and fastened to a portion of said vertical rod appreciably removed from the top for exerting an upward pull on said iron, and an iron rest affixed to said rod, whereby said rod, bar, rest and spring are rotatable as a unit in response to movement of said iron to either side of said rod.

8. A pressing mechanism comprising a vertical rotatable rod, a bar pivotally supported intermediate the ends thereof and mounted on said vertical rod, a pressing iron supported from one end of said bar, a contractile spring depending from the other end of said bar and fastened to said rod for exerting an upward pull on said iron, and an iron rest affixed to said rod and extending underneath said first mentioned end of said bar, whereby said rod, bar, and rest are rotatable as a unit in response to movement of said iron to either side of said rod.

9. The combination with a pressing mechanism comprising a vertical hollow rotatable rod, a vertical standard within said hollow rod for supporting the same, said rod being removable from said standard by lifting the same, a bar for supporting an iron at one end thereof pivotally supported intermediate the ends thereof and mounted on the top of said vertical rod, a contractile spring depending from the other end of said bar and fastened to a portion of said vertical rod appreciably removed from the top for exerting an upward pull on said iron, whereby said rod, bar and spring are rotatable as a unit in response to movement of said iron to either side of said rod, of a table, and a pressing board detachably fastened to said table, the top of said table having an aperture through which said vertical rod extends, said rod being mounted below said table top.

SIDNEY J. BEDELL,
EDWARD GLASSER.
